Horace [Signature]

Attorney.

UNITED STATES PATENT OFFICE.

JOSEPH S. MITCHELL, OF CHICAGO, ILLINOIS, ASSIGNOR TO SULLIVAN MACHINERY COMPANY, A CORPORATION OF MASSACHUSETTS.

CORE DRILL.

Application filed July 11, 1924. Serial No. 725,519.

My invention relates to core drills.

An object of my invention is to provide an improved core drill and relates especially to improved core lifter mechanism for such a drill. Another object of my invention is to provide an improved core drill having an improved core lifter mechanism having improved means for the passage of fluid to the drill bit. Still another object of my invention is to provide an improved core lifter mechanism having great flexibility and strength provided with improved means formed therein for the passage of mud fluid to the drill bit. These and other objects and advantages of my invention will hereinafter more fully appear.

In the accompanying drawings I have shown for purposes of illustration one form which my invention may assume in practice.

20 In these drawings,—

Fig. 1 is a central longitudinal sectional view through a core barrel and drill bit in which my improved core lifter mechanism is incorporated.

25 Fig. 2 is a transverse sectional view taken substantially on line 2—2 of Fig. 1.

Fig. 3 is a detail vertical sectional view taken substantially on line 3—3 of Fig. 2.

In this illustrative form of my invention I 30 have shown a core barrel 1 threadedly secured as at 2 at its lower end to a core lifter shell or casing 3 provided with a conical bore 4 in which my improved core lifter, generally designated 5, is disposed, to be 35 hereinafter described. The lower end of the core lifter casing 3 is threadedly secured at its lower end as at 6 to a drill bit 7, herein of the well known rotary diamond type.

The core lifter 5 comprises a split resilient 40 sheet metal spring member 8 of conical shape to which a plurality of radially spaced wedge-shaped core engaging members 9 are suitably secured, herein by rivets 10. The wedge members 9 are provided with concave 45 vertical inner surfaces 11 and at their lower ends with outwardly inclined surfaces 12 which are adapted to direct and guide a core 13 upwardly through the core lifter into the core barrel 1 in the usual manner. The 50 spaces between the wedges permit the passage of mud fluid or the like to the drill bit.

55 In my improved construction it will be observed that a plurality of radially spaced apertures 14 are provided intermediate the

wedge members 9 in the resilient member 8 a 55 short distance below the upper edge thereof which permit the passage of the mud fluid from the interior of the core barrel 1 laterally through the apertures 14 around the exterior of the core lifter and downwardly 60 to the cutting edges of the drill bit 7, the mud fluid then passing upwardly around the core barrel clearing the cuttings from the bit and from the hole.

In the use of my improved core lifter mechanism it will be noted that during the drilling operation the core 13 passes upwardly through the core lifter into the core barrel. During this operation the bottom of the core lifter tends to cling to the core 65 and is forced upwardly against the bottom edge of the core barrel, cutting off the flow of fluid over the top of the core lifter. When the inner lower surfaces of the wedges are 70 worn down, the core 13 obstructs the passage 75 of fluid between the wedges at their lower ends consequently preventing the mud fluid from passing through the spaces between the wedges, the fluid then passing to the drill bit through the apertures 14, there being 80 ample clearance between the wedges at the top of the lifter. If the apertures 14 were omitted, a heavy pressure would build up in 85 the core barrel, forcing the core lifter downward, practically cutting off the supply of mud fluid and further wearing the inside of the wedges rendering the core lifter useless. By the use of the apertures 14 in the core lifter this is avoided, the fluid passing freely 90 through the core lifter even when worn.

As a result of my improvement it will be 95 noted that a core lifter of improved form is provided having great elasticity and strength and improved means for permitting the free passage of mud fluid, even when in a worn condition, to the drill bit. It will also be noted that the core lifter may be applied to core drills of a standard form with a minimum of change.

While I have in this application specifically described one form which my invention 100 may assume in practice, it will be understood that this form of the same is shown for purposes of illustration and that the invention may be modified and embodied in 105 various other forms without departing from its spirit or the scope of the appended claims.

What I claim as new and desire to secure by Letters Patent is:

1. A core lifter mechanism comprising a resilient core lifter member having spaced 5 radially projecting wedge shaped portions, and means for permitting the lateral passage of fluid therethrough comprising radial openings formed in said member intermediate said portions.
  - 10 2. A core lifter mechanism comprising spaced wedge shaped core engaging elements, a resilient member connecting said elements, and means for permitting the lateral passage of fluid therethrough comprising radial openings formed in said member intermediate said elements.
  - 15 3. A core lifter mechanism comprising a resilient spring member, spaced wedge shaped core engaging portions projecting 20 inwardly therefrom, and means for permitting the lateral passage of fluid therethrough comprising radial openings formed in said spring member intermediate said portions.
  - 25 4. A core lifter mechanism comprising a resilient member, spaced wedge shaped core engaging members secured thereto, and means for permitting the passage of fluid laterally therethrough comprising radial 30 openings formed in said resilient member intermediate said core engaging members.
  - 35 5. A core lifter mechanism comprising a resilient member of truncated conical form, a plurality of spaced core engaging elements secured thereto, and means for permitting the passage of fluid laterally through said member including radial openings formed in said member intermediate said elements.
  - 40 6. A core lifter mechanism comprising a tapered split spring member, a plurality of spaced wedge shaped core engaging elements
- secured thereto, and means for permitting the lateral passage of fluid through said member comprising radial openings formed in said member intermediate said elements. 45
7. A core lifter mechanism comprising an annular split spring, a plurality of spaced inwardly projecting wedge shaped core engaging elements secured thereto, and means for permitting lateral passage of fluid 50 through said spring comprising radial openings formed in said spring intermediate said element.
8. A core lifter mechanism comprising an annular split spring of truncated conical 55 form, a plurality of spaced inwardly projecting core engaging elements secured thereto, and means for permitting the lateral passage of fluid through said spring comprising radial openings formed in said 60 spring intermediate said elements.
9. A core lifter mechanism comprising a resilient spring member, spaced core engaging portions projecting inwardly therefrom, and means for permitting the lateral 65 passage of fluid through said spring comprising radial openings formed in said spring adjacent the upper edge thereof and intermediate said core engaging portions.
10. In a core drilling mechanism, a core 70 barrel, a drill bit carried thereby, a resilient core lifter comprising a split spring member and spaced inwardly projecting core engaging portions thereon, and means for permitting the passage of fluid from said barrel laterally through said lifter to said bit comprising radial openings in said spring member intermediate said spaced core engaging portions. 75

In testimony whereof I affix my signature.

JOSEPH S. MITCHELL.
